CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed May 18, 1921. Serial No. 470,565.

My invention relates to electric switches, and particularly to a multiple device. The object of my invention is to provide a fitting of compact arrangement in which a group of switches is assembled to independently control a group of circuits—for instance, a group of independent lighting units. The switch is preferably of the flush type, as illustrated in the accompanying drawings, in 10 which

Fig. 1 is a plan view of a flush switch with cover plate removed, and in which my invention is embodied in one form;

Fig. 2 is a longitudinal section there- 15 through;

Fig. 3 is a plan of a porcelain body with the switch mechanisms removed;

Fig. 4 is an inverted plan thereof; and

Fig. 5 is a transverse section through the 20 switch.

In house-wiring systems, it frequently happens that it is desirable to control at a single point a group of separate lighting circuits, for instance, a group of wall lights 25 and two groups of chandelier lights. The present invention provides a compact multiple switch in which each circuit is independently controlled, the mechanism being of such compact arrangement that the insulating body of the switch may be housed 30 within an ordinary one-gang outlet box.

As here shown, the present fitting comprises a cup-shaped insulating body 6, of generally rectangular shape, across the open 35 face of which extends a yoke piece 7 resting on ledges 8 on the opposite end walls of the body, and secured in position by screw bolts 9 passing through the end walls of the body and taking into tapped holes in laterally extended lugs 14 adjacent the ends of 40 the yoke. The latter is provided with terminal ears 10 which extend beyond the ends of the body and are slotted at 11 to receive the screws by which the fitting is mounted

45 upon the lugs 12 of the outlet box 13, dia- grammatically illustrated in Fig. 2. The yokes are also tapped at their opposite ends adjacent the laterally projecting lugs 14 to receive the screws 15, by which the cover 50 plate 16 may be secured in position over the installation to house-in the switch and impart a finish to the installation in the usual manner. The cover plate is provided with a longitudinally extending bowed portion 17

at intervals transversely slotted at 18 to accommodate the operating members for the several switches.

The body 6 is laterally channeled at 19 to receive the leading-in main which is engaged by the binding screw 20 and clamped thereby against the terminal plate 21 seated on the depressed ledge 22 adjacent the groove 19. The terminal plate 21 is secured in position by a screw bolt 23 passing through the body 6 and engaging a connecting strap 24 let into the lower face of the base. Screw bolts 25 and 26 respectively, also engaging the strap 24, connect the latter with the terminal plates 27 and 28, arranged on opposite sides of the switch body and longitudinally spaced from each other and from the terminal plate 21. Associated with the several terminal plates 21, 27 and 28, and preferably integral therewith, are switch terminals 29, 30 and 31 respectively. Diametrically opposite each of these terminals is a co-operating terminal 32, 33 and 34, respectively, each having an associated binding screw 35, 36 and 37 for connection with the distributing circuits controlled by the several switches. To accommodate the wires leading to these several circuits, the side walls of the insulating body are channeled at 38 and 39, the channel 38 being of sufficient width to accommodate the branch wires from the wire terminals 35 and 36, together, while the channel 39 accommodates the branch wire leading from the terminal 37.

Controlling the several circuits are independent switch mechanisms of the toggle type. The details of these mechanisms may be variously modified, and inasmuch as they form no part of my invention, need not be described in detail. Each mechanism operates an oscillating switch bar 40, which makes or breaks connection between the terminals for the respective switches. This switch bar is carried by a yoke 41 pivoted at 42 on a switch frame 43, and is actuated through a switch spring 44 and rocker 45 in a well-understood manner. The rocker 45 is also pivoted at 46 on the switch frame and is provided with an actuating thumb-piece 47 working in the slot 18, which is substantially closed against the admission of foreign matter, to the switch chamber, by an arcuate shield 48. The latter may be

used to carry switch indicating legends, one or the other of which is visible through the slot 18 in the face plate, dependent upon the position of the switch mechanism.

5. The frames 43 of the several switch mechanisms are of U-shape, the base of the U being slotted at 49 to accommodate the legs of the yoke 45. Rivets 50 at opposite ends of the bottom of the frame secure the latter 10 to outwardly extending bays 51 spaced along the length of the yoke 7, which is also slotted at 52 to accommodate the rocker.

As will be recognized, the arrangement shown affords an extremely compact arrangement for a distributing switch of the type mentioned. The mounting of the several switch mechanisms independently upon the yoke makes it possible to use standard switch mechanisms for the purpose. The 20 independence of the several mechanisms makes it possible to vary the number of switches according to the requirements of the installation; thus, if but a single switch is needed the face plate will have but a single 25 slot 18, and only a single switch mechanism will be mounted on the yoke to connect the terminals 30 and 33. If only two switches are desired, those at opposite ends of the switch chamber will be installed, omitting 30 the intermediate mechanism, while the face plate is slotted to accommodate only the two rockers at opposite ends of the yoke 7. The base 6 may be uniform for all of these variations, thus reducing the number of different 35 porcelains required in different types of installation.

Various modifications in detailed construction will readily occur to those dealing with the problem, without departing from what 40 I claim as my invention.

I claim—

1. An electric switch, comprising a cup-shaped insulating base, a carrying yoke extending longitudinally of the chambered base 45 above its open face, independent pairs of cooperating switch terminals longitudinally spaced apart within the chamber of said base each of said pairs comprising terminals on opposite sides of the switch chamber, independent snap switch mechanisms mounted on said yoke and respectively cooperating with the terminal pairs, together with a shunt strap let into the lower face of the base and electrically connecting together one 50 terminal of each pair, associated means for connecting thereto a leading-in wire, and means associated with the other terminal of each group for connecting thereto a branch wire.

60. 2. In an electric switch, a cup-shaped insulating body of generally rectangular contour, a switch-carrying yoke extending longitudinally of said body above the open face thereof, in combination with a series of 65 switch mechanisms supported on said yoke,

each of said mechanisms comprising a pivoted switch bar rocking in a plane transverse to the longitudinal plane of the yoke and adapted to cooperate with switch contacts supported at opposite sides of the 70 chamber.

3. An electric switch, comprising a cup-shaped insulating body, laterally grooved to receive leading-in and distributing wires, the grooves for said wires being arranged on 75 opposite sides of the base and certain of said grooves being of sufficient size to accommodate a plurality of wires therein.

4. An electric switch, comprising a cup-shaped insulating base, a wire terminal at 80 one side of said base for establishing electrical connection with a leading-in wire, strap means let into the lower face of said base and electrically connected to said terminal, in combination with a plurality of 85 switch terminals longitudinally spaced on opposite sides of said base and projecting into the switch chamber, certain of said terminals being electrically connected to the said leading-in wire terminal through said 90 strap means.

5. An electric switch, comprising a cup-shaped insulating base adapted to receive a plurality of switch mechanisms within its switch chamber, a yoke extending longitudinally across the open face of the switch chamber and adapted to carry a group of switch mechanisms, at least one switch mechanism mounted on said yoke, a wire terminal mounted on said base to receive a 100 leading-in wire, an associated switch terminal, seats on said base for a group of branch-line terminals, a branch-line terminal mounted on one of said seats, and a switch terminal associated therewith and arranged to operate with the switch terminal associated with the terminal for the leading-in wire. 105

6. An electric switch comprising an insulating body recessed from one face to form a substantially rectangular switch chamber 110 channelled on its opposite sides, switch contacts arranged in the channels on the opposite sides of the chamber, a supporting yoke extending longitudinally of the chamber across the open face thereof, independent 115 switch mechanisms mounted on the yoke, a switch bar for each mechanism adapted to make and break connection with switch contacts lying in channels on opposite sides of the switch chamber, and conductors carried 120 by the base and establishing permanent electrical connection between certain of said switch contacts.

7. An electric switch comprising an insulating body recessed from one face to form 125 a substantially rectangular switch chamber channelled on its opposite sides, switch contacts arranged in the channels on the opposite sides of the chamber, a supporting yoke extending longitudinally of the chamber 130

across the open face thereof, independent switch mechanisms mounted on the yoke, a switch bar for each mechanism, said switch mechanism operating on its associated switch bar to cause the same to rock transversely of the switch chamber to make and break connection with switch contacts lying in channels on opposite sides of the switch chamber, and conductors carried by the base and establishing permanent electrical connection between certain of said switch contacts.

8. In an electric switch, a unitary switch base having a line wire terminal and shaped

to accommodate a plurality of switch contacts electrically connected to said line wire terminal, and a corresponding plurality of cooperating switch contacts, together with a supporting yoke for the base overlying the latter and adapted to support independent switch mechanisms for making and breaking connection between any desired pair of cooperating switch contacts.

In testimony whereof I have signed my name to this specification.

CARL ERIC ANDERSON.
